UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

TEMPERATURE-CONTROLLING MEANS FOR PLATE-CASTING BOXES.

1,197,894.

Specification of Letters Patent. Patented Sept. 12, 1916.

Application filed April 17, 1915. Serial No. 22,154.

To all whom it may concern:

Be it known that I, HENRY F. BECHMAN, a citizen of the United States, residing at Battle Creek, in the county of Calhoun and State of Michigan, have invented certain new and useful Improvements in Temperature-Controlling Means for Plate-Casting Boxes; and I hereby declare that the following is a full, clear, and exact description 10 thereof, reference being had to the accompanying drawings, which form part of this specification.

This invention relates to stereotype plate casting boxes, and its object is to maintain the parts of the casting box at a temperature most suitable for plate casting and prevent overheating thereof, so that plates may be cast in such boxes more uniformly and with greater rapidity than has been heretofore 20 practical with casting boxes of the same general type but to which this invention has not been applied.

The invention is particularly designed for use in connection with "tubular plate" 25 stereotype casting boxes of the type shown in my Patent No. 945,678, of January 4, 1910, but is applicable to other forms of plate casting boxes. I will explain the invention as applied to such a "tubular" plate 30 casting box, and set forth in the claims the essential features of the invention for which I desire protection.

In the accompanying drawings forming part of this specification: Figure 1 is a sectional elevation of part of a tubular plate casting box provided with my novel temperature regulating means. Fig. 2 is a detail sectional view of such box showing the core in position for removing a cast plate. 40 Fig. 3 is a detail transverse section on line 3—3, Fig. 1.

The box indicated in the drawings is a "tubular plate" casting box of the type shown in my aforesaid patent, and comprises a base 7 to which are secured side frames 9 upon which is mounted a drag 1 provided with a semi-cylindric recess in its front face to accommodate a tiltable core 2, when the latter is in casting position.

To the drag 1 is hinged a cope 1^a which can be swung to and from the drag, and has a semi-cylindric recess in its inner face so that when the box is closed, as indicated in Fig. 3, the opposed recesses in the drag

and cope form a cylindric chamber within 55 which the core is axially disposed.

The core 2 is mounted on trunnions 3 journaled in the side frames 9, so that said core can be swung to a position axially of the said chamber, (Figs. 1 and 3) when a 60 plate is to be cast; and when the box is opened said core can be tilted outwardly to a substantially horizontal position, as indicated in Fig. 2, to facilitate the removal of the cast plate. Such core has been heretofore 65 made hollow and provided with interior pipes suitably connected with exterior water supply and exhaust pipes by which water can be circulated through the box during the casting operations.

The parts thus far described are substantially the same as those shown in my aforesaid patent and are not specifically claimed herein.

It is desirable in casting boxes both to 75 prevent overheating of the part with which the molten stereotype metal directly contacts during the casting operations, and at the same time to prevent such sudden or excessive changes in temperature of such parts 80 as would affect the uniformity of plates cast therein. The water circulating systems heretofore employed have not given the desired results. In applying my invention to such a box the said core is made hollow and 85 preferably has a passage 3^a in its bottom which opens into the chamber in the core at the side which will be highest when the core is lowered (as in Fig. 2), and which passage 3^a communicates with a port 3^b in 90 one of the core trunnions 3, which is connected, at the outer end of the trunnion, to an elbow 4, and said elbow 4 may be connected by a flexible pipe or hose section 4^a to a pipe 5 leading into a reservoir or tank 95 6 mounted on any suitable support, as 8, at any desired elevation.

The tank is preferably so situated with respect to the box that the fluid will circulate through the connecting pipe from the 100 tank to the box and a sufficient supply of cooling fluid from the tank will be maintained within the hollow member of the box.

The pipe 5 preferably extends within the tank to a point above the normal water level 105 therein, (which is indicated at *w* in Fig. 1), and the part of said pipe within the tank is preferably numerously perforated, as in-

dicated in the drawing. A water gage 6^a attached to the tank enables the proper level of water therein to be determined.

The water or medium in the tank may be 5 initially heated to a desired temperature by external means, not shown, and will ordinarily be heated by the core which is heated by the molten metal during the casting operations. When I herein refer to "water"

10 I do not intend to restrict the invention to use of water as the heating or cooling medium.

When the box is ready for casting a plate, the core 2 is in a vertical position (Fig. 1), 15 and the core and all the connections between it and the tank below the water line *w* are filled with hot water which prevents its overheating and at the same time prevents its sudden chilling, because the water is 20 kept at approximately boiling point during the casting operations.

The temperature of the water in the tank is maintained at about boiling point by the heat derived from the molten metal around 25 the core during the plate casting operations; and on the other hand the temperature of the core will be maintained at an approximately uniform temperature by the body of hot water constantly maintained 30 therein at approximately boiling point. The lowering and raising of the core causes an ebb and flow of hot water into the core each time the core is lowered to remove a plate; which maintains the core at a safe 35 practically uniform casting temperature without requiring a constant circulation of water or steam through the box.

It will be seen that a considerable body 40 of water remains in the core at all times, and if any steam collects in the core when the box is closed its escape is facilitated when the core is lowered, and water enters the core immediately after any steam escapes into the tank.

45 A casting box equipped with this invention can be maintained at a temperature of about 200°, which is very desirable, for if the box is chilled suddenly or irregularly the plates are chilled unequally while being cast and must therefore be machined before they can be used. Further my invention prevents overheating of the box, and at a temperature of about 200° the plates will not stick; but if the box was not 50 protected from overheating it might become so hot that the stereotype metal would adhere thereto, causing great annoyance and delay; but with boxes equipped with my invention, plates can be cast as fast as 55 60 the operators can manipulate the box.

What I claim is:

1. In a stereotype plate casting apparatus, the combination of a casting box having a hollow member, a tank exterior to the box, and a single fluid conduit connecting 65 said tank with the lower part of said member, whereby a substantially constant supply of fluid may be maintained within said hollow member.

2. In a stereotype casting apparatus the 70 combination of a casting box having a hollow tiltable member, a tank exterior to the box, and a single fluid conduit connecting said tank with the lower part of said member, substantially as described. 75

3. In stereotype casting apparatus; the combination of a box having a hollow member, a tank exterior to the box, and a pipe connecting said tank with the lower end of said hollow member, said pipe serving both 80 for inlet and outlet of fluid to and from said member whereby a substantially constant supply of fluid may be maintained within said hollow member.

4. In stereotype casting apparatus; the 85 combination of a box having a hollow tiltable member provided with an opening in its lower end, a tank exterior to the box, and a pipe connecting said tank with the opening in said member, said pipe serving 90 both for inlet and outlet of fluid to and from said member, whereby a substantially constant supply of fluid may be maintained within said hollow member.

5. In stereotype casting apparatus; the 95 combination of a box having a hollow core and provided with a trunnion having an opening communicating with the interior of the core; a tank exterior to the box, and a pipe connecting said tank with the opening in said trunnion, said pipe serving to 100 conduct fluid to and from the core whereby a substantially constant supply of fluid may be maintained within said core.

6. In a stereotype casting apparatus the 105 combination of a box having a hollow tiltable core provided with a hollow trunnion communicating with its interior, a tank exterior to the box, and a pipe connecting said tank with said trunnion for maintaining a 110 substantially constant supply of fluid within said tiltable core.

In testimony that I claim the foregoing as my own, I affix my signature in presence of two witnesses.

HENRY F. BECHMAN.
